ABSTRACT

A numeral pin setting mechanism in a calculating machine or the like apparatus, wherein a mechanism is provided for operating a column shifting mechanism, and is operatively associated with the individual numeral keys by the drive of a motor.

NUMERAL PIN SETTING MECHANISM IN
CALCULATING MACHINES AND THE LIKE APPARATUS

The present invention relates to a numeral pin setting mechanism in a calculating machine or the like apparatus.

A conventional numeral pin setting mechanism of the type described is so constructed that when a selected one of numeral buttons, respectively carrying numerals 0-9, is depressed, a pin corresponding to the numeral of said numeral button which is stored in the known pin carriage is pushed forward and at the same time a column shifting lever cooperative with each numeral setting lever and adapted to restrain or release said pin carriage is operated to shift the column one pitch.

In such a numeral pin setting mechanism as described above, shifting of the columns one at a time is effected by the tensile strength of a spring which is restrained or released. Therefore, in order to increase the speed of the numeral pin setting operation, the tensile strength of the spring has to be made large so as to improve the responsive characteristic. However, there is a limitation in increasing the speed of the numeral pin setting operation because, since the force required for operating the numeral key is attributed mostly to the load of said spring, the key touch will become objectionably heavy if the tensile strength of the spring is increased.

The object of the present invention is to provide a numeral pin setting mechanism in a calculating machine or the like apparatus, which provides for a soft key touch and enables the speed of the numeral pin setting operation to be increased.

The numeral pin setting mechanism according to the present invention is characterized by the fact that the drive of a motor is utilized for operating a column shifting mechanism operatively associated with the individual numeral keys, whereby the key touch is made light.

The present invention will appear more clearly from the following detailed description when taken in connection with the accompanying drawings, showing by way of example a preferred embodiment of the invention.

FIG. 1 is a plan view showing a preferred embodiment of the numeral pin setting mechanism according to the present invention;

FIG. 2 is a side view showing the position of the mechanism with the numeral keys being in their stationary positions;

FIG. 3 is a side view showing the position of the mechanism with one of the numeral keys being depressed;

FIG. 4 is a side view illustrating the operation of the column shifting mechanism;

FIG. 5 is a cross-sectional view taken on the line A—A of FIG. 2 and

FIG. 6 is a cross-sectional view taken on the line B—B of FIG. 2.

Referring to the drawings, numeral 1 designates a numeral setting lever which is, as shown in FIG. 2, pivotably supported by a cut lug 2a of a key board 2 and biased in a clockwise direction by a spring 3. Numeral 4 designates a pin pushing lever having one end pivotably connected to the lower end of the numeral setting lever 1 and the other end extending through a slit, formed in a guide plate 5, for sliding movement therein, said guide plate 5 being secured to a machine frame. The pin pushing lever 4 is formed with a projection 4a which, as shown in FIG. 1, is in abutting engagement with an upright arm of a sensing lever 7 which has one end slidably extending through the guide plate 5 and the other end slidably extending through another guide plate 6 secured to the machine frame. Numeral 8 designates a pivot lever having one end pivotably mounted on a pin 9 fixed to the machine frame and the other end connected to the sensing lever 7. Numeral 10 designates a connecting lever by which a swing lever 12, pivotably mounted on a shaft 11 fixed to the machine frame, and the pivot lever 8 are operatively connected with each other. Numeral 13 designates a transmission lever having one end connected to the swing lever 12 and the other end being bent upright and formed with U-shaped slot 13A in said upright portion (see FIG. 5) in which a depressing lever 15, rotatably

mounted on a fixed pin 14, is received. The transmission lever 13 and the depressing lever 15 are yieldingly connected with each other by a spring 16. The depressing lever 15 is formed with a bent lug 15b which is in engagement with a clutch lever 21 to be described later. Numeral 17 designates a driven lever pivotably mounted in a fixed pin 18 and always being held in the position shown in FIG. 2 by a stopper 19, fixed to the machine frame, and a spring 20.

The clutch lever 21 is pivotably mounted on a pin 22 fixed to the driven lever 17. A positioning lever 24 is pivotably mounted on a pin 23 which is also fixed to the driven lever 17. One end 24a of the positioning lever 24 is received in a recessed portion 21A of the clutch lever 21, as shown in FIG. 2, by the action of a spring 25. A clutch claw member 26 is constantly driven in a clockwise direction from a motor (not shown) and held out of engagement with the clutch lever 21. Numeral 27a designates a connecting lever by which a swing lever 27, pivotably mounted on the shaft 11, and the driven lever 17 are operatively connected with each other. Numeral 28 designates a connecting lever connecting a pivot lever 31 with swing lever 27 (see FIG. 1), which pivot lever 31 has one end pivotably mounted on a pin 29 fixed to the machine frame. A carriage shifting lever 30 has one end in sliding engagement with a slit of the guide plate 5 and the other end in sliding engagement with a slit of the guide plate 6, and is urged by a spring 32 in the direction of the arrow a. Another carriage shifting lever 33 is pivotably mounted on a fixed shaft 34, and held in engagement with the carriage shifting lever 30 at the position of a projection 30a of the latter (see FIG. 2) under the biasing force of a spring 35. A pin carriage 36 is pivotably mounted on a rod 37 provided on the machine frame, and accommodates therein pins 38 corresponding to the numerals 0-9. The pin carriage 36 is provided with column shifting stoppers 39. The above-described construction of the pin carriage 36 is the same as that known in the art. A spring 40 acts on the pin carriage 36 to pull it upward as viewed in FIG. 1, that is, in a direction of higher columns.

Now, the operation of the numeral pin setting mechanism of the invention constructed as described above will be explained hereunder: In FIG. 2, when a selected one to the numeral setting lever 1 (one corresponding to the numeral 5 in the illustration) is depressed, the corresponding pin 38 is pushed forward by the pin pushing lever 4 in the direction of the arrow b, and at the same time the sensing lever 7 is also moved in the same direction by the projection 4a of said pin pushing lever 4. The motion of the sensing lever 7 is transmitted to the transmission lever 13 through the members 8, 10 and 12, causing the same to move in the direction of the arrow c. Since the depressing lever 15 is received at its portion 15a in a slot 13a formed in the transmission lever 13 in the way as shown in FIG. 6, it is pivoted in a clockwise direction. As a result, the clutch lever 21 in engagement with the bent lug 15b of the depressing lever 15 is pivotably moved in a counterclockwise direction about the pin 22 and brought into engagement with the clutch claw member 26 (See FIG. 3). Thus, the driven lever 17 is pivotably moved about the shaft 18 in a counterclockwise direction, together with the lever 21, by the clutch claw member 26 which is rotating in a clockwise direction. The clutch claw member 26 and the clutch lever 21 are in such positional relation that the extent of engagement therebetween will become increasingly large, once they have been engaged with each other even slightly. Therefore, the spring 25 is only required to be of a strength sufficient to cause a return movement of the clutch lever 21. The amount of the pivotal movement of the clutch lever 21 can be adjusted by a projection 21a of said clutch lever and a bent lug 17a, of the driven lever 17. The movement of the driven lever 17 is finally transmitted to the column shifting lever 30 through the members 27a, 27, 28 and 29 operatively connected to said drive lever, to cause the same to slide in the direction of the arrow b. Column shifting by the spring 40 is prohibited by the engagement between the column shifting lever 33 and the "0" pin 38a of the pin carriage 36. However, when the column shifting

lever 30 is moved in the direction of the arrow *b* incident to the pivotal movement of the driven lever 17, the column shifting lever 33 in engagement with said column shifting lever 30 at the projection 30a is turned clockwise to be disengaged from the "0" pin 38a (see FIG. 4), so that the pin carriage 36 is shifted about one-half pitch under the biasing force of the spring 40 and stopped thereat due to the engagement between the column shifting lever 30 and the stopper 39.

The clutch claw member 26 and the clutch lever 22 are arranged such that they are held in engagement only for a period necessary for the movement of the column shifting lever 30. When the clutch lever 21 is released from engagement with the clutch claw member 26 as shown in FIG. 4, it is returned to the stationary position of FIG. 2 by the action of the spring 25. It will, therefore, be appreciated that the driven lever 17 can return to the stationary position under the biasing force of the spring 20, without engaging the clutch claw member 26. The return movement of the driven lever 17 releases the column shifting lever 30, so that said column shifting lever is returned to the position of FIG. 2 and the column shifting lever 33 is also returned to the original position under the biasing force of the spring 35. Since the engagement between the column shifting lever 30 and the stopper 39 is released, the pin carriage 36 is again liberated and shifted under the biasing force of the spring 40. Thus, the column shifting lever 33 is again brought into engagement with the "0" pin 38a of the next column and shifting of one column is accomplished. By this step, a complete cycle of the numeral pin setting operation is completed.

If the next cycle of operation is performed, with the previously operated numeral setting lever 1 being held in its depressed position, an error in calculation result or mechanical locking will result. According to the present invention, the mechanism is provided with a safety device to ensure that the operation described above be completed in one cycle without fail. Namely, the bottom of the U-shaped slot 13A of the transmission lever 13 is located in substantially the same horizontal level as the pin 14. As the depressing lever 15 is rotated clockwise by the transmission lever 13, the bottom of the U-shaped slot 13A is depressed by the depressing lever 15 in engagement therewith and, when the engagement between the clutch lever 21 and the clutch claw member 26 has been completed, the portion 15a of said depressing lever is released

from engagement with the transmission lever 13 and is returned to the stationary position shown in FIG. 2 under the biasing force of the spring 41, overcoming the spring 16.

In the conventional mechanism, the numeral pin setting lever is operated with a force which is sufficient to overcome the frictional force created by the tensile strength of the column shifting spring 40, to release the engagement between the column shifting lever 33 and the pin carriage 36, and hence the operation becomes heavy. According to the present invention, however, use is made of the drive of a motor to effect the numeral pin setting operation. Therefore, the key touch can be made light and furthermore the operational speed can be increased by increasing the tensile strength of the column shifting spring 40 independently of the key touch.

15 What is claimed is:

1. A numeral pin setting mechanism for a calculating machine or the like comprising,
a plurality of manually operable keys (1),
a pin box (36),
a pin pushing lever (4) operatively connected with each key,
a rotating clutch claw member (26),
a clutch member (21) engageable with said clutch claw member in response to actuation of any said pin pushing lever by operation of the associated key to set a pin in said pin box,
and column shifting means (17, 27a, 27, 28, 29, 30) responsive to actuation of said clutch member (21) by said clutch claw member (26) for shifting said pin box by one column on each numeral setting operation.

30 2. The mechanism of claim 1 in which said column shifting means comprises a driven lever (17) which is rotatable about a fixed pivot in response to engagement of said clutch member with said clutch claw member, and means responsive to the turning of said driven lever for releasing said pin box to permit column shifting of said pin box.

35 3. The mechanism of claim 1 in which said responsive means includes a column shifting lever (33) which normally blocks shifting by said pin box, and lever means (27a, 27, 28, 29, 30) for actuating said column shifting lever to a non-blocking position in response to the turning of said driven lever.
